UNITED STATES PATENT OFFICE.

THOMAS J. TAYLOR, OF HOMER, LOUISIANA.

LIGHT-SUPPORT.

1,130,773.

Specification of Letters Patent.

Patented Mar. 9, 1915.

Application filed February 7, 1914. Serial No. 817,281.

To all whom it may concern:

Be it known that I, THOMAS J. TAYLOR, a citizen of the United States, residing at Homer, in the parish of Claiborne and State of Louisiana, have invented certain new and useful Improvements in Light-Supports, of which the following is a specification, reference being had to the accompanying drawings.

This invention relates to new and useful improvements in supports, and more particularly to swinging supports especially adapted for use in supporting electric lamps, the main object of the invention being to provide a support of the above character having carried thereby means whereby the lamps may be supported at any desired height or in any suitable position.

Another object of the present invention is the provision of a supporting device of the above character which will possess advantages and points of efficiency and durability, is inexpensive to manufacture and at the same time is of extremely simple construction and operation.

With the above and other objects in view as will become apparent as the description proceeds, the invention consists in certain constructions, combinations and arrangements of the parts that I shall hereinafter fully describe and claim.

For a full understanding of the invention, reference is to be had to the following description and accompanying drawings, in which—

Figure 1 is a side elevation of a supporting device constructed in accordance with my invention; Fig. 2 is an enlarged perspective view of one of the catch members; Fig. 3 is an enlarged sectional view taken on the line 3—3 of Fig. 1. Fig. 4 is a modification.

In carrying out my invention I provide a supporting rod 1, the upper end of which is threaded, and mounted thereon is a securing plate 2, said plate being provided with a plurality of openings whereby the same may be readily secured in any suitable manner to the ceiling, as shown in Fig. 1. The lower end of the supporting rod 1 is screw threaded as indicated at 3, and mounted for rotation thereon is a sleeve 4, said sleeve being supported in position by means of the nut 5 which is threaded upon the lower end 55 of the supporting rod 1 and arranged be-

tween the sleeve 4 and the nut 5 is a washer 6 which will eliminate friction between the sleeve 4 and the nut 5.

The sleeve 4 is adapted for rotation upon the lower end of the supporting rod 1 and formed integral therewith is an outwardly projecting supporting arm 7 which is adapted to be normally disposed in a substantially horizontal position and rotate around the lower end of the supporting rod 1. The sleeve 4 is held against upward sliding movement upon the supporting rod 1 by means of an annular flange 8 which may be either formed integral with the rod or removably secured thereto in any suitable manner. Secured to the supporting arm 7 and arranged in spaced relation are the resilient catch members 9 through which the light cord 10 is adapted to extend and is yieldably retained in any adjusted position so that the lights 11 which are suspended from the lower ends of the cords 10 may be held at any desired height and adjusted by releasing the catch members 9 so that the cords 10 may be readily drawn therefrom.

From the above description taken in connection with the accompanying drawings, it will be readily apparent that the lights 11 may be placed in any desired position in the room by the rotation of the supporting arm 7 and may be positioned at any desired height by adjusting the cords 10 within the catch members 9. It will be apparent that the cords 10 may be connected to the electric circuit at one side of the securing plate 2 or they may extend up through the plate at a point adjacent the center thereof. Adjustably mounted upon the arm 7 are a plurality of sleeves 7^a and extending outwardly from said sleeves are the supporting arms 8^a which may be provided with catch members 9. It will be noted that the sleeves 7^a may be quickly and readily adjustable upon the arm 7 and securely held in an adjustable position by the set screws 9^a. The catch members will be formed by striking a portion of the material out of the arms 8^a to form a resilient tongue 10'. From this it will be apparent that when the cord 10 is passed up from the openings by cutting material out it will be securely held by downward movement of the tongue 10' engaging therewith. It will be apparent that my improved supporting device can be quickly and readily set up in an effective position or readily

taken down and at the same time is extremely simple in construction and can be manufactured at a comparatively small cost.

In Fig. 4 I have illustrated a side elevation of a modified form of my invention wherein the supporting arm 7' extends upon opposite sides of the rod 1' and removably secured to the supporting arm 7' are the hooks 8' and adapted to be engaged by the 10 upper links of the chains 9'. This form of the invention is preferably to be used in supporting oil lamps and the like, said lamps being mounted within a wire bracket which is indicated by the numeral 12, the upper 15 end of which is provided with a hook, as shown at 13 and adapted to engage with any of the links of the chain to suspend the lamps from the supporting arm 7'. This form of the invention is to replace the preferred form when using the device where a 20 supply of electricity cannot be obtained.

While I have shown and described the preferred form of my invention it will be obvious that various changes in the details 25 of construction and in the proportions may be resorted to for successfully carrying my invention into practice without departing from the spirit and scope of the appended claim.

Copies of this patent may be obtained for five cents each, by addressing the "Commissioner of Patents, Washington, D. C."

What is claimed is:

In a device of the class described including a supporting plate having a threaded opening therein, a substantially perpendicular supporting rod having its end removably engaged within said opening, a sleeve rotatably mounted upon the lower end of said rod, means for retaining said sleeve against sliding movement upon the rod, an arm formed integral with the sleeve and projecting outwardly at an angle with respect to the supporting rod, a plurality of sleeves 35 slidably mounted upon said arm, supporting arms formed integral with the sleeves and extending outwardly therefrom, set screws carried by the sleeves and adapted to retain the same in adjustable position and catch members formed by the striking out portion 40 of the material at the supporting arms to provide resilient tongues as and for the purpose set forth.

In testimony whereof I hereunto affix my signature in the presence of two witnesses.

THOMAS J. TAYLOR.
